UNITED STATES PATENT OFFICE.

MYRON H. CLARK, OF HASTINGS-UPON-HUDSON, NEW YORK, ASSIGNOR TO BOSTON RUBBER SHOE COMPANY, A CORPORATION OF MASSACHUSETTS.

FORM FOR VULCANIZABLE PLASTIC ARTICLES.

1,209,671.

Specification of Letters Patent. Patented Dec. 26, 1916.

Application filed March 2, 1915. Serial No. 11,607.

To all whom it may concern:

Be it known that I, MYRON H. CLARK, a citizen of the United States, and a resident of Hastings-upon-Hudson, county of Westchester, and State of New York, have invented certain new and useful Improvements in Forms for Vulcanizable Plastic Articles, of which the following is a full, clear, and exact description.

10 My invention relates to improvements in forms for use in connection with the vulcanization of articles made from rubber, rubber-like, or similar materials and fiber.

It is customary in the manufacture of articles of this character to form the article on the outside of a rigid support or form and subject the outer surface of the article to pressure which is resisted by the form, while allowing the escape of entrapped air, 20 gases, and other deleterious fluids from the interior of the article by maintaining portions of said article beneath its outer surface in communication with the interior of the form in which a vacuum may be maintained. Usually this process is carried out during vulcanization of the article so that the article is vulcanized in the required shape simultaneously with the removal of the entrapped air and the like. In place of 25 the vacuum, pressure is often employed upon the interior of the article, said interior pressure being met by a greater pressure upon the exterior of the article. In either case it is essential that the condition of the 30 article being treated shall be, as to its pressure condition, at all times under the control of the operator. During this controlled differential pressure cure, it has hitherto been difficult to maintain an accurate differential 35 pressure due to leakage through the wall of the form resulting in a partial equalization of the pressure.

The object of my invention, therefore, is to so treat the form that leakage through 45 its wall will be positively prevented, and this I accomplish, preferably by producing an impervious coating upon the wall of the form which completely seals the wall of the form, as will be hereinafter more fully described.

One apparatus for carrying the invention into effect is illustrated in the accompanying drawing in which: Figure 1 is a sectional view through a form for a boot embodying my improvements; Fig. 2 is a frag-

mentary view showing the modification; Fig. 3 is a fragmentary view showing another modification.

Referring to the drawing, 10 designates a support or form upon which the article is built, in this case a boot form is shown, the same being hollow and having a plurality of orifices 11 in its wall which expose the boot 12, during cure, to the differential of pressure above described. The form is provided 60 with a closure 13 making the interior air tight. A pipe 14 leads into the interior of the form whereby the interior may be brought into communication with a suction pump or pressure pump (not shown), there 70 being a fluid regulating device 15 operatively connected with the pipe to vary the pressure within the form.

The form may be made of any desired rigid material, but is preferably made of 75 aluminum, which on account of its strength and light weight is particularly advantageous. However, there exists a certain porosity in aluminum which renders its use somewhat impractical for this purpose, but 80 this is also true of wood and even other metals besides aluminum to a more or less extent. Therefore to fit the form, whether made of wood, metal, or other desired material, for use in connection with the differential pressure curing of vulcanizable articles, I preferably apply to the wall of the 85 form an impervious coating 16 which seals the pores of the material from which the form is made and positively prevents leakage through the wall of the form.

Any desired coating material, which will seal the pores of the particular material from which the form is made, may be used, and I have found the varnish known as 95 Japan to be particularly suited for use in connection with aluminum forms.

I contemplate also the use of a sealing material which, contrary to being applied merely as a superficial coating may be impregnated or worked into the somewhat cellulose structure of wood, metal, or other material from which the form is made.

In the drawing I have illustrated various positions of the impervious coating upon the 105 form, such as for instance in Fig. 1, the coating is shown as covering the entire interior face of the form: in Fig. 2, the coating is shown confined merely to the exposed outer face of the form beyond the boot; and 110

in Fig. 3, the coating is shown as confined to the inner face of the form beyond that portion of the form occupied by the boot. I do not limit myself to any particular location of the coating shown, since I contemplate localizing or even generally applying the coating, or even impregnating the material from which the form itself is made, without restriction as to area or other dimensions, it being simply necessary to the practice of my invention that all or any of the pores of any material from which the form is made be sealed against leakage under the influence of a differential pressure cure.

Having described my invention, what I claim and desire to have protected by Letters Patent is:

1. A hollow form for supporting a vulcanizable plastic article during a differential pressure cure, means for exposing the interior and exterior of the form to a differential of pressure, and an impervious material sealing and preventing leakage through the pores of the form so that the internal and external pressure upon the form may be accurately controlled.

2. A hollow metallic form for supporting

a vulcanizable plastic article during a differential pressure cure, means for exposing the interior of the form to a lesser pressure than the exterior of the form, and an impervious coating, sealing and preventing leakage through the pores of the form so that the internal and external pressure upon the form may be accurately controlled.

3. A hollow form for supporting a vulcanizable plastic article having a passage way affording communication between the interior and exterior of the form within the area adapted to be covered by the article, and a superficial coating for the form to enhance its imperviousness.

4. A hollow form for supporting a vulcanizable plastic article having a passage way affording communication between the interior and exterior of the form within the area adapted to be covered by the article, and a coating upon the interior of the form to enhance its imperviousness.

Signed at New York, this 26th day of Feb., 1915.

MYRON H. CLARK.
